VALVE TAPPET

Joseph L. Dostal, Birmingham, Mich., assignor
to Eaton Manufacturing Company, Cleveland,
Ohio, a corporation of Ohio

Application June 18, 1938, Serial No. 214,492

7 Claims. (Cl. 123—90)

This invention relates to valve tappets of the barrel type and particularly to such valve tappets that are of a one-piece cast type, and has particular reference to the rough cast blank from which such valve tappets are formed, the principal object being the provision of a blank for such tappet that particularly lends itself to the production of different forms of such tappets and to tappets formed from such blanks having certain novel features of construction rendering them particularly advantageous for use.

Objects of the invention include the provision of a one-piece cast hollow blank for a barrel type valve tappet so constructed and arranged that by machining away various portions thereof valve tappets of different forms may be produced from identical blanks; the provision of a valve tappet blank as above described provided with more than two solid transverse walls; the provision of a one-piece cast hollow valve tappet blank having opposite end walls and an intermediate wall, the side walls of the tappet on either side of the intermediate wall being provided with windows therethrough; and the provision of a one-piece hollow cast iron valve tappet blank including three axially spaced transverse walls and hollow cylindrical connecting walls, that portion of the hollow cylindrical walls connecting the intermediate wall with each of the end walls being provided with a plurality of windows therethrough, and the windows on one side of the intermediate wall being angularly staggered with respect to the windows on the opposite side thereof.

Other objects of the invention include the provision of a valve tappet comprising a hollow cylindrical body portion each end of which is provided with a group of angularly spaced windows extending therethrough, the windows in one group being staggered angularly about the axis of the tappet with respect to the windows in the group at the opposite end of the tappet; the provision of a one-piece, hollow, cast barrel type valve tappet the peripherally outer walls of which are provided at one end with three equally angularly spaced windows therethrough and three equally angularly spaced windows at the opposite end thereof, the windows at one end being angularly staggered with respect to the windows at the opposite end; the provision of a valve tappet of the type just described having three axially spaced transversely extending solid walls; the provision of a one-piece hollow cast valve tappet having opposite end walls and an intermediate wall, the side walls of the tappet

on either side of the intermediate wall being provided with a plurality of windows therein; the provision of a valve tappet as last described in which the windows on one side of the intermediate wall are angularly staggered with respect to the windows on the opposite side thereof; and the provision of a one-piece hollow valve tappet of cast construction provided with a plurality of windows in the side walls thereof which windows are so arranged as to distribute the wearing surfaces of the tappet in such a manner as to result in even wearing of the peripheral surfaces thereof in service.

The above being among the objects of the present invention the same consists in certain novel features of construction and combinations of parts to be hereinafter described with reference to the accompanying drawing, and then claimed, having the above and other objects in view.

In the accompanying drawing which illustrates suitable embodiments of the present invention and in which like numerals refer to like parts throughout the several different views,

Fig. 1 is a partially broken, partially sectioned side elevational view of one form of a rough cast tappet blank constructed in accordance with the present invention;

Fig. 2 is a view similar to Fig. 1 but illustrating a slightly modified form of construction;

Figs. 3 and 4 are transverse sectional views taken on the lines 3—3 and 4—4, respectively, of either Figs. 1 or 2;

Fig. 5 is a vertical sectional view taken axially through one form of finished tappet which may be formed from the blanks shown in Figs. 1 or 2;

Figs. 6 and 7 are views similar to Fig. 5 but illustrating machining of the blank to provide different types of tappets;

Fig. 8 is a vertical sectional view taken axially through a completed tappet formed from the blank shown in Fig. 2 and machined to provide a threaded opening for reception of a conventional valve clearance adjusting screw;

Fig. 9 is a top plan view of the tappet shown in Fig. 8.

In one-piece hollow cast iron valve tappets it is conventional practice to provide a plurality of windows in the side walls thereof. In the past these windows have been arranged either in one group around the tappet and consequently each in angularly spaced relation with respect to its neighbor, or else have been provided in two groups with the windows of one group axially aligned with the windows of the other group.

This arrangement in conventional tappet practice has resulted in areas of increased wear in service angularly about the axis of the tappet which is undesirable in practice. According to 5 the present invention this detrimental feature of conventional valve tappets of the type referred to is overcome by forming a group of windows in the tappet adjacent each end of the tappet, the windows of each group preferably 10 being equally angularly spaced about the axis of the tappet, and the windows of one group being angularly staggered with respect to the windows of the other group, this having the effect of providing a more even distribution of 15 the wearing surfaces angularly about the axis of the tappet than in conventional constructions.

Conventional tappets of the type referred to are provided with a maximum of two transverse walls one located at each end of the tappet. 20 Particularly where the side walls of the tappet are unusually thin, being substantially unsupported in their central portion, they are not only subject to warpage and other deformation in service, but they also offer certain difficulties in 25 machining and grinding. The present invention provides a construction wherein this difficulty in conventional constructions is avoided by the provision of an additional cross or transverse wall intermediate the length of the tappet. Not 30 only does this intermediate wall serve to strengthen the side walls of the tappet against deformation but in certain cases it may further serve as a supporting wall for a push rod or other valve operating part. Particularly where the 35 windows for the tappet are arranged in groups on opposite sides of the intermediate wall advantages result not possible in this type of tappet constructed in accordance with conventional practice.

40 The present invention particularly deals with a rough cast tappet blank of such construction and arrangement that by the use of identical blanks a plurality of structurally different valve tappets may be produced. The advantage of the 45 present invention in this respect is that it is necessary to cast only one type of blank and then by machining the blank differently different structural types of valve tappets may be produced in any desired quantity.

50 Referring now to Fig. 1 of the drawing which 55 illustrates a valve tappet blank in condition received from the foundry, that is in rough cast condition, it will be noted that it includes a hollow approximately cylindrical side wall portion 10 having a solid integral top end wall 12 closing such end, a solid integral bottom end wall 14 closing the corresponding end and the axially outer portion of which is formed of chilled cast iron as indicated at 16, and an intermediate integral solid wall 18. The wall 18 may be formed 60 at any desired location axially of the tappet between the walls 12 and 14 but for the purpose of illustration is shown as being located slightly closer to the wall 14 than to the wall 12. As 65 indicated in Fig. 1 the peripheral surface of the tappet blank is illustrated as being formed to correspond to the outer surfaces of two truncated cones arranged in axial alignment and with their small ends in abutting relationship, 70 this conformation resulting from the preferred method of casting this type of tappet and as necessitated by the draft required to withdraw the pattern for the same from the mold. This feature, however, has no importance as far as 75 the present invention is concerned and the pe-

ripheral surfaces of the blank may be considered truly cylindrical as far as the present description is concerned. The side wall portion 10 above the intermediate wall 18 is provided with a plurality of windows 20 therethrough and the 5 side wall portion between the walls 14 and 18 is provided with a plurality of windows 22 therethrough. In the broader aspects of the present invention the windows 20 and 22 may be provided in groups of any desired number, but in 10 a more limited aspect of the present invention there are preferably three windows 20 and three windows 22, the windows 20 being angularly staggered about the axis of the tappet with respect to the windows 22. It may be noted that the 15 metal of the side walls 10 about the margins of both the openings 20 and 22 is inwardly rounded or beveled as at 24, this being desirable in the finished product in order to eliminate any sharp cutting edges at the margins of the various windows which might serve to scrape oil off of the bore in the internal combustion engine provided for reception of such tappet.

The tappet blank illustrated in Fig. 2 is identical to the tappet blank illustrated in Fig. 1 except in one particular, and, accordingly, corresponding parts are indicated by corresponding numerals. The only difference between the tappet blank illustrated in Fig. 2 and that illustrated in Fig. 1 is that in Fig. 2 the upper wall 12 is 30 provided with an axially outwardly projecting boss 26 formed integrally therewith and the purpose of which will be described in detail in connection with the description of Figs. 8 and 9.

It may be noted that the relation of the diameter of the tappet and tappet blanks shown in the accompanying drawing compared to the length thereof is conventional and will usually be of a ratio not exceeding one to three. It may also be noted that particularly where there 40 are three windows 20 and three windows 22 and the windows 20 are angularly staggered with respect to the windows 22, the only successful method of casting these tappet blanks commercially in large quantities, as far as I am aware, 45 is that disclosed in my co-pending application for Letters Patent of the United States filed on even date herewith for improvements in Method of making valve tappets and the like, and serially numbered 214,491.

50 Referring now to Fig. 5 one type of completely machined and finished valve tappet is shown and which may be constructed from either of the blanks illustrated in Figs. 1 and 2. Ordinarily it will be constructed from a blank such as shown 55 in Fig. 1 for the reason that no axially extending boss such as the boss 26 is necessary at one end thereof. The valve tappet shown in Fig. 5 is identical to the blank shown in Fig. 1 except that the peripheral surfaces thereof have been 60 machined to perfectly cylindrical conformation from end to end and the opposite end faces thereof have been machined flat. Technically speaking the exposed surface of the chilled portion 16 of the bottom end wall 14 is too hard to 65 be machinable in the ordinary sense of the word and because of its hardened character a grinding operation must be relied upon to bring it to the smooth flat condition demanded in the final product. For the purpose of ease and simplicity 70 in description, in view of the fact that the finished valve tappets illustrated in Figs. 5 to 9, inclusive, are identical to corresponding portions of the rough blanks illustrated in Figs. 1 and 2, corresponding parts are indicated by correspond- 75

ing numerals in these later views and, accordingly, as far as the tappet shown in Fig. 5 is concerned, no further description of the same is necessary.

5 The valve tappet illustrated in Fig. 6 is identical to the valve tappet illustrated in Fig. 5 except that the upper wall 12 is machined to provide a central opening 28 therein, to accommodate the passage of a valve push rod downwardly therethrough, and the upper surface of the intermediate wall 18 is provided with a partially spherical pocket or recess 30 therein for reception of the lower end of such push rod, this type of construction being favored under some circumstances. Obviously the valve tappet shown in Fig. 6 may be constructed from a blank as shown in either Figs. 1 or 2 although ordinarily the blank shown in Fig. 1 will be employed as in such case it necessitates only machining the wall 20 12 to provide the opening 28, whereas if the blank shown in Fig. 2 were employed it would be necessary to also remove the boss 26.

The valve tappet illustrated in Fig. 7 is identical to the valve tappets illustrated in Figs. 5 25 and 6 except that in this case not only is the upper wall 12 machined to provide a central opening 28 therein but the intermediate wall 18 is machined to provide a similar opening 32 therein, the opening 32 being provided for the same purpose as the opening 28, namely to permit the passage of a valve push rod downwardly therethrough and in such case the upper surface of the bottom wall 14 will preferably be formed to provide a partially spherical or otherwise 35 shaped recess or pocket 34 therein for the reception of the lower end of a push rod as is desirable in some cases. It may be noted that in the construction illustrated in Figs. 6 and 7 the diameters of the openings 28 and 32 may be such 40 that while a push rod may be loosely received therein they will serve as a guide in directing the lower end of the push rod into the corresponding pocket 30 or 34 provided in such case.

The tappet illustrated in Figs. 8 and 9 is 45 identical to the blank illustrated in Fig. 2 except that the peripheral surfaces thereof have been machined to provide a true cylinder, the outer face of the bottom wall 14 has been machined in the same manner as the tappets previously 50 described and the corresponding outer face of the end wall 12 has been machined to form the boss 26 into a true cylinder, preferably to provide a pair of flats 36 at diametrically opposite sides thereof for reception of a wrench, and to provide 55 an axially threaded opening 38 in the boss 26 and through the end wall 12 for reception of a suitable or conventional valve clearance adjusting screw (not shown).

From the above it will be understood that all 60 of the tappets illustrated in Figs. 5, 6, 7 and 8 could be produced from identical blanks of the type shown in Fig. 2 and that all of the tappets shown in Figs. 5, 6 and 7 could be produced from identical blanks of the type shown in Fig. 1. The 65 tappets shown in Figs. 5 and 8 being provided with three axially spaced solid transverse walls, the side wall portions of the tappet are reinforced to a maximum extent against distortion and warpage or the like, and even where the wall 12 70 or both the walls 12 and 18 are machined to provide a central opening therein as illustrated in Figs. 6 and 7, respectively, that portion of the walls 12 and 18 remaining provide inwardly projecting rib portions which impart a material 75 added rigidity to the tappet. It will also be ob-

served that in all of the tappet constructions shown the windows 20 are angularly staggered with respect to the windows 22 so that the tappet is provided with a substantially uniform wearing surface circumferentially of the same. Accordingly, the construction provided embodies a number of novel and advantageous features not found in heretofore suggested constructions. 5

Formal changes may be made in the specific embodiments of the invention described without departing from the spirit or substance of the broad invention, the scope of which is commensurate with the appended claims. 10

What I claim is:

1. A blank for a valve tappet comprising, in combination, a hollow generally cylindrical body portion, and three axially spaced imperforate transverse walls integrally joined thereto. 15

2. A one-piece blank for a valve tappet comprising, in combination, a hollow generally cylindrical body portion, an end wall closing one end of said body portion, an end wall closing the opposite end of said body portion, and a transverse wall integrally joined to said body portion interiorly thereof and in axially spaced relation 20 with respect to said end walls, all of said walls being imperforate. 25

3. A blank for a valve tappet comprising, in combination, a tubular body portion, an end wall adjacent one end of said body portion integrally 30 united thereto, an end wall adjacent the opposite end of said body portion integrally united thereto, and a solid transverse wall within said body portion intermediate the first two mentioned walls. 35

4. A valve tappet comprising a generally cylindrical hollow body portion and an imperforate end wall integral therewith at each end thereof, said body portion adjacent one end thereof having three openings therethrough arranged in approximately equally angularly spaced relation 40 with respect to each other and with their longitudinal center lines substantially parallel to the axis of said body portion, said body portion having three like openings therethrough adjacent the opposite end thereof and arranged in 45 approximately equally angularly spaced relation with respect to each other, said openings adjacent one end of said main body portion being angularly staggered with respect to the said openings at the opposite end thereof. 50

5. A valve tappet comprising a generally cylindrical hollow body portion, a wall integrally united thereto and closing one end of said body portion, the axially outer face of said wall being of a relatively hard nature, a second wall positioned 55 interiorly of said main body portion intermediate the ends thereof and integrally united thereto, said second wall having a pocket formed centrally thereof in the face thereof opposite the first mentioned wall, and a radially inwardly projecting rib on the interior surface of said main body portion in axially spaced relation with respect to said second wall and on that side thereof opposite the first mentioned wall. 60

6. A valve tappet comprising a generally cylindrical hollow body portion, a transverse wall integrally united thereto adjacent each end thereof, a third transverse wall positioned interiorly of and integrally united to said main body portion intermediate the first two mentioned walls, said main body portion having a group of openings therethrough between said third wall and each of the first two mentioned walls, the openings of each of said groups being arranged in angularly spaced relation, and the 75

axially outer portion of one of the two first mentioned walls being of a relatively hard and un-machinable nature.

7. A rough cast unmachined hollow integral barrel type valve tappet blank comprising, in combination, a pair of axially spaced imperforate transverse walls, a hollow cylindrical main body

portion connecting said walls and having a window therethrough, said main body portion around the margins of said window being inwardly relieved whereby to eliminate the occurrence of a sharp edge at said margin after machining said blank. 5

JOSEPH L. DOSTAL.
